MATERIAL SUBDIVIDING INSTALLATION

Oliver W. Randolph, Toledo, Ohio

Application February 3, 1941, Serial No. 377,083

2 Claims. (Cl. 83—93)

This invention relates to classifying, mixing, and handling of bulk material as from grinding or milling operations.

This invention has utility when incorporated in flow control for efficient definite feeding, mixing, and commingling of fines.

Referring to the drawings:

Fig. 1 is a diagrammatic showing of a flow sheet in connection with which there is associated the mixing control herein;

Fig. 2 is a detail view in plan, with parts broken away, of the mixer of Fig. 1;

Fig. 3 is a fragmentary end elevation from the right of Fig. 2; and

Fig. 4 is a section on the line IV—IV, Fig. 2.

In the carrying out of the invention herein, say in the subdividing of material such as alfalfa, chopped feed may be received at station 1 of Randolph Patent No. 2,205,175, of June 18, 1940, and elevated therefrom by pneumatic conveyor 2 by way of duct 3 to cyclone dust collector 4 having discharge 5, at which valve control arm 6 may be operated for flow therefrom to be into duct or "pants" leg 7 or "pants" leg or duct 8. These ducts 7, 8, have respective open spill connections 9, 10. The open spill connection 9 is connected say through down duct 11 with grinder or hammer mill 12 of Randolph Patent No. 2,226,741, of December 31, 1940. Therefrom there is draw-off way 13 to pneumatic elevator 14 having riser duct 15 to cyclone dust collector 16. In practice, surplus gas and dust from the dust collector 4 may pass therefrom by riser way 17, and the solids or fragment portions, say short cuttings of alfalfa as well as the leaves, may initially preferably go to the break-down hammer mill 12. In the instance of difficulty at the mill 12, the valve or control 6 may be operated for flow by way of the duct 8 and connection 10 to down duct 18 and by way of hopper 19 to hammer mill 20, set up in parallel with the hammer mill 12.

This stock, whether or not pre-subdivided in the hammer mill 12, say in the break-down initial operation, may now pass from the mill 20 by take-off way 21, pneumatic elevator 22, and riser duct 23 to cyclone dust collector 24 in parallel with the cyclone dust collector 16 in the flow installation herein.

The cyclone dust collector 16 has from its discharge 25 valve controls 26, 27, the manipulation of which may be effective for flow discharge from the cyclone dust collector 16 by way of duct 28 to bag filling means 29, say for a coarse

or general type of feed. This may be say for straight run cut hay.

In lieu of the discharge through this duct 28, there may be control of the valves 26, 27, for flow from the dust collector 16 by way of duct 30 to receiver 31. Motor 32 (Fig. 2) has shaft 33 with belt 34 therefrom to pulley 35. In the receiver 31 is shaft 36 carrying worm conveyor 37 having remote from the pulley 35 gear 38 with 10 detachable connection 39 assembling such with the shaft 36. This gear 38 is in mesh with pinion 40 having detachable connection 41 with shaft 42 in the receiver 31. On this shaft 42 is fast the drive pulley 35 and screw conveyor 43 15 in parallel with screw conveyor 37 and adjacent thereto. In practice, the clearing runs, for an 8 or 9 inch diameter conveyor, in the region of $\frac{1}{4}$ to $\frac{3}{4}$ inch for the clearance between the flights of the conveyor 31 with the conveyor 43. While 20 gear 38 and pinion 40 may be of similar diameter for like speed of rotation in the event the conveyors 31, 43, be of similar pitch, at such time there would be equal response in withdrawing material or propelling material from the receiver 25 31 in opposite directions for delivery by the conveyor 37 to down duct 44 and by the conveyor 43 to down duct 45. However, in practice advantage has been experienced with retention of similar pitch for the respective conveyors 37, 43, and 30 ready substitution of different diameter between the toothed means on the shafts 36, 42. In the instance herein shown, such is taken as 2 to 1 or thereabouts, which means that the follower or driven shaft 36 operates the conveyor 31 at 35 approximately one-half the volume of delivery rate of operation of the conveyor 43. This would mean that, as to the spill in the receiver 31 from the down duct 30, one-third thereof would go to the down spout 44 and two-thirds to the down 40 spout 45. In the event either toothed member be removed from its shaft, there is left but one propeller effective and, accordingly, with such the shaft 42 there is delivery throughout only to the down spout 45.

45 This down spout or duct 45 herein delivers to shaker screen 46. Inasmuch as this may, in the set-up herein, be for the breaker or initial separation or subdivision of the material, this screen 46 may be of larger capacity or say even of the two decker type. The fines, as passing through this subdivision at the screen 46, may be by take-off duct 47 having discharge 48 to humidifier control equipment of Randolph application for United States Letters Patent, Ser. No. 323,581, filed March 12, 1940. However, there may be in-

termmediate or bulk storage or direct bagging or packaging.

The offal or matter which passes over the screen 46 may, by duct 49 and hopper 19, go to the hammer mill 20 and there have regrinding occur. These hammer mills 12, 20, may be for single or double grinder separation and, in the double grinder set-up, work toward increased capacity with reduction of power requirement in the installation operation. This material, as from the hammer mill 20 on say the reground material, is elevated to the cyclone 24. These cyclones 16, 24, have dust take-offs or risers 50. 51, respectively.

The valve controls 26, 27, from the discharge 25 of the cyclone 16 are operable not only for the down duct 28 or the down duct 30 but to control independently thereof for flow from this cyclone 16 by way of duct 52. This duct 52 has straight-away direct communication to the duct 45 and is thus an effective bypass as to the mixer receiver 31 and in feeding from this cyclone 16 directly to the shaker screen 46. The cyclone 24 from its outlet or discharge 53 has valve controls 54, 55, thereby effective to direct discharge from the cyclone 24 by way of down duct 56 to the receiver 31, and by way of down duct 57 to discharge 58 as to a bagger, humidifier or storage; by way of down duct 59 directly to the down duct 44 in bypassing the mixer receiver 31. Cut-off valve 60 is supplemental control against disturbance at the mixer from functioning of the cyclone 24. Likewise, slide cut-off valve 61 is a safeguard when the down duct 52 is not in use, for eliminating any disturbance in the mixer 31 as from the dust collector 16.

The down spout 44 or duct from the receiver 31 may be to shaker screen 62 for thereby handling the fines of the regrind and working through for the finer grades in the meal. In the controls herein the sieves, working on such material as alfalfa, have a tendency to develop therefrom even from the screen 46 as well as from the screen 62 over way fluff or woolly fiber portions. This may be from the screen 62 taken off only in a minor or negligible extent by down duct 63 in communication say with humidifier, storage, or packaging. More fluff passes at spout 64. Its flow in this installation is such as may be delivered to the dust collector 24 to have such pass by way of the mixer 31 in a uniformly definitely mixed relation for working into the feed. This means that there can be, uniformly disseminated throughout the entire mass, such protein or fiber material to leave the meal as low as 17 per cent or even 13 per cent. From this screen 62 as the fines are reground for supplemental effectiveness, the coarse flows therefrom by way of down the spout 64 to the hopper 19 for the regrinding hammer mill 20, for ascent to the cyclone 24 and from thence to go say directly to bagger, humidifier by way of the duct 57 or again to the mixer, or directly to the screen 62 and the discharge therefrom by the way 63.

It is to be noted that as to these screens control valve 65 may cut off the spout 41, control valve 66 may cut off the spout 49, control valve 67 may cut off the spout 64, and control valve 68 may cut off the spout 63.

The flexibility of this flow installation as adapted under the receiver and screw mixer therewith has meant in practice for subdivision of stock a saving of as much as 25 per cent in horse power requirement for mill operation to the degree of fines, say in the handling of alfalfa

initially cut to 2 inch lengths as cut green and dehydrated. With this installation, the controls for flow are from maximum of output with resulting efficiency therefrom, and in such controls the 5 take-offs may be for a range or ranges of fines or proportions of fiber as may conform to various specifications. This flexibility in control is a matter of appeal to the mill operator and of advantage in conforming to trade demands and 10 character of stock handled.

The pneumatic elevators 2, 22, 14, in the general flow handling herein are centrifugal blowers, thereby supplying not only delivery of the stock but also sufficient air for effecting the cyclone separation. Disturbance from this blower 2 into the cyclone 4 is not transmitted to the hammer mill 12 or 20 due to the open connections 9, 10. In the practice hereunder, the control may be selective for all to go to the mill 12 from the cyclone dust collector 4, or such flow diverted from flow into the duct 7 for emergency flow into the duct 8 as shown by the position of the control handle 6 (Fig. 1). As the equipment for grinding operation proceeds in its functioning for continuity of handling materials, there may be equalization of the loads in the various elements of grinders and screens as well as to the character of stock to be worked out from the mill. To such end, the mill 20 may be the regrind wholly or nearly so, while the mill 12 is for the initial break-down. In working up this character for output, homogeneity throughout is important, and the mixer receiver 31 is efficient to such end. There may be original break-downs 20 from the mill 12 supplied by the duct 30 to be commingled with regrinding portions from the duct 56. Such may be delivered in proportions or 25 selectively as desired to the respective or selected screen.

The range of simplifying herein extends not only to installation but to the operation. For the installation the drive from the motor 32 may be at such speed reduction as to rotate the shaft 42 at say 300 R. P. M. Whether the shaft 36 be rotated or disconnected, this operation of the shaft 42, due to the screw conveyor 43, is effective for conducting spill from the spout 56 over into spill from the spout 30 and so commingling such that there is uniform dissemination of the portions 30 commingled in the discharge 45. In the event the shaft 36 be simultaneously operating with the shaft 42, the screw conveyor 37 likewise, although as specifically shown it is at a reduced rotative rate, draws its one-half proportion of the mixer 35 quantity not only from the down spout 30 but from the down spout 56 so that there is discharge into the down spout 44 of one-third uniformly mixed for the sifter 62 as against the two-thirds proportion in the spout 45 for the greater capacity 50 or two deck sifter 46. A factor in contributing 55 to this mixing, especially when the conveyor 43 is working simultaneously with the conveyor 37 is the urge from the direction of rotation of these screw conveyors upward and outward, which promotes the mixing as a loosening action as the material receiving sides of the conveyors travel upward and away from each other. This works out as effective for reducing the actual running of the fines and seems so to divide up the coarser 60 that in the handling, even to the milling operations, such is a minimum. This in practice has resulted in higher carotin content for the feed, which can accordingly be run for a higher proportion, say of 20 per cent protein value, from alfalfa 65 as cut green and dehydrated.

2,312,478

3

For simplifying the installation as against clogging anywhere or back due to improper shifting of slides, there is proper experience to eliminate the slide valves 60, 61, as to the supply to the mixer and the slide valves 65, 66, 67, 68, in the discharges from the screens or sifters. However, in the working of the stock to eliminate the portions not going through the screens or to select such as coarse, the down spout 49 may be shifted from its spill connection 68 as to the mill 20 and thus have spill therefrom go to the bagger, storage, or other disposal. Likewise as to the down spout 64, wherein this fluff or carry-over is even more pronounced than from the sifter 46. Accordingly, in the shifting of this spout 64 away from delivery to the mill 19 as permitted by the connection 69, this flow from the spout 64 may be bagged, put in storage, or have other removal from further flow in the installation hereunder.

What is claimed and it is desired to secure by Letters Patent is:

1. A comminuting system for pre-cut bulk vegetable material consisting of a dust collector provided with a material inlet and a plurality of material outlets, a fan means with an elevating conduit, said conduit delivering material upwardly to the inlet of the dust collector, two outlet conduits leading downwardly from the material outlets of the dust collector, valve means to deliver material from the collector into either of the two conduits; a primary impact mill and a secondary impact mill, conduit feed means for each mill, interconnections between one of each conduit feed means and one of each outlet conduits from the dust collector; discharge means leading from each mill comprising a fan and an elevating conduit; a pair of dust collectors each provided with a material inlet and a plurality of material discharge outlets, inter-connections between one of the elevating conduits of each mill and the ma-

terial inlet of one of the paired dust collectors, a plurality of discharge conduits from each of the paired collectors, proportioning means in communication with one discharge conduit from each of the paired collectors, a pair of screen units, interconnecting conduits between the proportioning means and each of the paired screens, inter-connections between another delivery conduit from each of the paired collectors to each of the paired screens, each of said latter inter-connections being provided with a shut off means, a finished material conduit leading from beneath each screen to discharge the troughs from each screen, a recirculating conduit leading from above each screen to the conduit feed means on the secondary mill.

2. In combination a pair of mills, a pair of dust collectors, a conduit with pneumatic means to convey pulverized material from each mill to each dust collector, a housing enclosing a mixing and proportioning device, a conduit connecting each collector with said housing to convey solids to the proportioning device, a pair of separate screens, a conduit connecting the proportioning device with each screen, means in the proportioning device to mix materials and proportion the same to each of the last mentioned conduits; a second conduit leading from each collector to the housing of the proportioning device and positioned to discharge directly into one of the conduits connecting the proportioning device with a screen, valve shut off means in each of said second conduits positioned at entrance of said proportioning device, a conduit arranged to receive the overs from each screen and convey same to one of the mills and another conduit arranged to receive throughs from each screen and discharge same as finished product.

OLIVER W. RANDOLPH.
